SHOE WITH CHANNELLED WELT

Frank J. Tobacco, Staten Island, N. Y.

Application July 28, 1945, Serial No. 607,559

2 Claims. (Cl. 36—17)

1

This invention relates to the manufacture of articles of footwear, which will be referred to herein as shoes, although it is to be understood that that term is intended to include not only shoes but also similar types of footwear, such as slippers, pumps, etc. More particularly, the invention is concerned with a shoe of novel construction which can be manufactured rapidly and at low cost. The shoe of the invention is superior to prior similar shoes in that it is easier to make, because it does not require pulling over operations, and it is stronger and of better wearing quality but without any sacrifice in appearance.

The new shoe includes the usual upper, with or without a lining, a sock lining, and a welt, and these parts are secured together in preliminary operations by stitching the edges of the upper, the upper lining, if used, and the sock lining to the welt between the edges thereof. The welt is of elongated triangular cross-section and the edges of the upper, etc., are secured to the welt against one of the convergent sides thereof and pointing toward the thin edge of the welt. After these operations are completed, the shoe is slipped over a last of proper size, and the upper, sock lining, and welt are thus secured together in such manner as to fit the last snugly without the usual pulling over. The shoe may include a shank and an insole, although, in some shoes, either the shank or the insole may be omitted. When both a shank and an insole are employed, the insole is applied to the under surface of the sock lining and the shank applied to underlie the insole, after which the thin edge of the welt is turned inwardly under the edges of the insole and shank to hold those parts in place against the sock lining. An outer sole is then prepared by skiving material from one face along its edge to form a downwardly and outwardly sloping surface, and the outer sole is applied to the under surfaces of the welt and the shank and to the under surface of the insole beyond the forward end of the shank with the sloping surface on the outer sole in contact with the lower convergent side of the welt. The welt and outer sole are then secured together by appropriate means, as, for example, by a layer of cement or by stitching passing through the exposed portion of the welt at its thick edge and through the outer sole adjacent its outer edge. The welt employed is preferably formed with a lengthwise channel in one of its convergent sides and the edges of the upper and sock lining are stitched together and to the welt so that the edges beyond the stitching lie within the channel. The welt projects a substantial distance beyond

the channel toward its thin edge, and when the welt is turned inwardly to lie beneath the sock lining, the edges of the upper and sock lining lie within the channel and thus do not form a ridge in the interior of the shoe. The projecting convergent portion of the welt lying inward from the line of connection of the welt to the upper and sock lining provides additional stiffness and strength around the perimeter of the shoe at the sole, and this strengthening portion of the welt occupies the space formed by skiving the material from the sole. If desired, the welt may be made of the strip produced in the skiving operation, or it can be a separate piece of material previously prepared.

For a better understanding of the invention, reference may be made to the accompanying drawings, in which

Fig. 1 is a plan view of the sole for one form 20 of the new shoe;

Fig. 2 is a sectional view on the line 2—2 of Fig. 1;

Fig. 3 is a perspective view of one form of welt used with the new shoe;

Fig. 4 is a plan view of one form of upper that 25 may be used in the new shoe;

Fig. 5 is a transverse sectional view illustrating how the upper, upper lining, and sock lining may be stitched together along their edges before being 30 secured to the welt;

Fig. 6 is a view similar to Fig. 5, showing the securing of the connected edges of the upper, upper lining, and sock lining to the welt;

Fig. 7 is a transverse sectional view through 35 the new shoe adjacent the heel seat;

Figs. 8 and 9 are sectional views on the lines 8—8 and 9—9 of the shoe shown in Fig. 10;

Fig. 10 is a view in perspective of one form of the new shoe;

Fig. 11 is a longitudinal sectional view through 40 the heel of the new shoe at one stage in the manufacture; and

Fig. 12 is a view similar to Fig. 11 showing the completed shoe.

In the drawings, the new shoe is illustrated as including an upper 20, which may be made of any suitable material and in any desired style. This upper is provided with a lining 21 in the constructions shown, although such a lining may be 45 omitted, if desired, and the upper lining is secured to the upper edge of the upper by stitching in the usual way. The shoe also includes a sock lining 22 which is of relatively soft flexible material.

In making the shoe, the edges of the upper 20,

upper lining 21, and sock lining 22 are placed in registry, as shown in Fig. 5, with all the edges pointing in the same direction. The three edges are then secured together by a line of stitching 23. After the assembly of the upper, upper lining, and sock lining, the connected edges are secured to a welt 24. This welt is of elongated triangular cross section and it is preferably provided with a longitudinal channel 25 in one convergent side between its thick edge 26 and its thin edge 27. To secure the welt to the connected edges of the upper, upper lining, and sock lining, those edges are placed opposite the channel 25 in the welt to point toward the thin edge of the welt and are then secured to the welt by a line of stitching 28, which passes through the three edges and through the welt within the channel. The extreme edges of the upper, upper lining, and sock lining then lie within the channel as illustrated in Fig. 6.

The assembly made up of the upper, upper lining, sock lining, and welt may now be slipped over a last, after which an insole 29, if one is used, is applied to the exposed face of the sock lining. A shank 30 is then placed against the exposed face of the insole to extend from the heel seat forwardly throughout the arch portion of the shoe. The shank is made of any suitable material, such as leather or a fibrous composition, and it may be provided with a metal stiffener of the usual type, if desired. Preferably before the application of the insole and shank, they are skived off along their edges to form upwardly sloping surfaces on their undersides. After the insole and shank have been placed in position, the welt is turned inwardly so as to underlie the edges of the insole and shank and hold those parts in place.

When the shoe includes a counter, such as that indicated at 31, the lower edge 21a of the upper lining 21 is not connected to the lower edge of the upper and to the edges of the sock lining and the welt at the heel. When the welt has been applied to the upper and sock lining as previously described, the counter is inserted between the upper and the upper lining, and cement is applied to the upper lining along its free lower edge 21a on the surface opposite the upper and sock lining. When the assembly is then slipped over the last, the counter is forced snugly against the inner surface of the upper, the upper lining is similarly applied snugly against the inner surface of the counter, and the edges 21a of the upper lining and 31a of the counter are caused to lie flat against the surface of the sock lining. The cemented edge of the upper lining then adheres to the surface of the sock lining so that the counter is properly held in place. After the heel 32 has been nailed in place, a pad 33 is placed within the shoe to overlie the cemented edge 21a of the upper lining.

If the shoe is to have a box in the toe, the lower edge of the upper lining is left free at the toe, and the box in moist soft condition is inserted between the upper and upper lining before the upper is secured to sock lining and welt. Upon lasting, the toe box is properly shaped and hardened.

After the assembled parts described have been slipped on the last, the insole and shank placed in position, and the welt turned in under the insole and shank, an outer sole 34 is applied. This sole is prepared for application to the shoe by being skived on one face along its edge to remove a strip of material 35 of triangular cross-sectional shape generally the same as that of the felt. The skiving produces a downwardly and outwardly sloping surface 36 around the edge of the outer sole, and

the latter is placed against the insole and shank with sloping surface 36 in contact with the lower convergent side of the welt. The sole is then secured in place by any suitable means, as, for example, the lower side of the welt may be cemented to the sloping surface 36 of the sole, as shown in Fig. 9, or, in case the shoe is of the type having a projecting sole, as shown in Fig. 7, the exposed thick edge 26 of the welt may be secured to the sole by a line of stitching 37.

In shoes in which the welt is to extend entirely around the heel, as in the construction shown in Figs. 11 and 12, the edges of the upper 20 and the sock lining 22 are secured to the welt in the manner previously described throughout the length of those edges. In some shoes, the welt may terminate at the breast face of the heel or at the ball and instep, in which event, the free portion of the lower edge of the upper is provided with an extended flange and is secured to the under surface of the shank, which is attached to the under surface of the sock lining, by ordinary hand or machine lasting operations. Also, in some shoes, such as that shown in Fig. 10, the upper may not be continuous but consists of straps 38, 39 forward of the instep and a strap 40 just forward of the heel. In such a shoe, the edges of the straps and of the strap linings, if used, are connected to the sock lining and to the welt, while at the toe and heel and in the spaces between the straps, only the sock lining is connected to the welt.

In shoes, such as that shown in Fig. 9, in which a projecting sole is not employed, the welt is of appropriate width between its thick and thin edges, and the edges of the upper, upper lining, and sock lining are secured to the welt relatively close to the thick edge thereof. When the welt is then turned under the sock lining, only a narrow portion of the welt is exposed.

While I prefer in all constructions to connect the edges of the upper, upper lining, and sock lining to the welt throughout the portion of the shoe forward of the breast face of the heel, it is to be understood that this construction need not be employed throughout the portion of the shoe mentioned, and that conventional shoe making methods may be used to a greater or lesser extent. To obtain the full benefits of the invention, it is desirable to connect the edges of the upper, upper lining, and sock lining to the welt in the manner described, wherever that is permissible.

In the new shoe, the turning in of the welt beneath the sock lining along the perimeter of the latter gives added strength to the shoe along the line of connection of the upper to the sole. By making the welt of elongated triangular form and skiving the upper surface of the outer sole, the employment of the relatively wide welt does not interfere with forming the shoe with flat inner and outer surfaces. Also, by channeling the welt, space is provided to receive the reversely folded portions of the upper, upper lining, and sock lining, and the formation of a ridge on the inner surface of the shoe is thus prevented.

While the welt may be preliminarily formed of suitable stock, it is possible to use the strip of material 35 removed from the sole in the skiving operation as the welt. The use of the strip as the welt reduces the cost, and at the same time, insures that the welt and the outer sole will fit smoothly together.

What is claimed is:

1. A shoe which comprises an upper, a sock lining, a welt of generally triangular cross-section lying with its thin edge extending inwardly

beneath the sock lining, the welt having a longitudinal channel in its upper face, the edges of the upper and sock lining being turned inwardly and lying within the channel, said edges being secured to the welt through the bottom of the channel, an outer sole skived on its upper face along its edge to provide a sloping surface, the outer sole lying beneath the welt and sock lining with said sloping surface engaging the lower convergent face of the welt, and means for securing the welt to the outer sole. 10

2. A shoe which comprises an upper, a sock lining, a welt of generally triangular cross-section lying with its thin edge extending inwardly beneath the sock lining, the welt having a longitudinal channel in its upper face, the edges of the upper and sock lining being turned inwardly and lying within the channel, said edges being secured to the welt through the bottom of the channel, a shank lying against the under surface of the sock lining with its edge between the sock lining and the inturned portion of the welt, an outer sole skived on its upper face along its edge to provide a sloping surface, the outer sole lying against the under surface of the shank with its 20

5

sloping surface in contact with the lower face of the welt, and means for securing the welt to the outer sole. 25
